ORDNANCE CHAMBRAGE AND CARTRIDGE
CASE

Ralph Waldo Miller, Topango, and Edward Baden Powell, San Diego, Calif., assignors, by direct and mesne assignments, of seventy-five per cent to said Powell, Pasadena, Calif., and twenty-five per cent to said Miller

Application December 4, 1944, Serial No. 566,576

6 Claims. (Cl. 42—76)

1

This invention relates to the chambrage of ordnance and fire arms, and its primary object is to provide, by improved chambrage design, a higher efficiency with increased projectile velocities and energies without corresponding increase in the maximum pressures which are evolved in the chamber or behind the projectile.

Without going into the detailed underlying reasons, it may be stated in general that the velocity and energy which is imparted to a projectile of a given mass by a powder charge of given composition, depends upon several factors which include the amount of explosive which is burnt behind the projectile, the manner in which the combustion of the powder charge is controlled and also the manner in which resultant gaseous pressure is applied to the projectile.

Maximum permissible pressures are limited not only by existing ordnance structures and strengths but also by the fact that excessive pressures tend to induce uncontrollable detonation of the charge. Ability to burn a large charge of explosive behind a projectile depends largely on the control of combustion so as to generate gaseous pressure relatively slowly.

With a relatively slow combustion initiated at the breech end of a chamber or cartridge there is a tendency of the pressure developed initially at that point to force a large proportion of unburnt solid explosive forwardly along the chamber and barrel behind the projectile. That action not only tends to excessive wear of the chamber and barrel but also to inefficient use of the explosive energy.

One of the objects of our invention is to overcome the stated difficulties along with others, and, generally, to enable the efficient burning of a relatively larger powder charge behind a given projectile and to apply the resultant kinetic energy of the combustion gases to the projectile with higher efficiency than has heretofore been accomplished. Our invention makes it possible to burn a substantially larger charge of explosive behind a given projectile without any substantial increase in maximum pressures, and with combustion and application of the pressures to the projectile so controlled that the propulsion of unburnt powder behind the projectile is minimized and the application of gaseous pressure and the flow of pressure gas behind the projectile is so controlled as to give the projectile a relative increase in velocity and energy which is greater than the relative increase in the mass of the charge.

In rifle chambrages, or cartridges, of the type

2

where the chamber diameter is larger than the bore, we have discovered that the shape of the chamber neck is a factor having unexpected controlling functions. We have discovered that if the chamber neck be made in a venturi conformation instead of conical or "bottlenecked" as in all standard chambers, the difficulties which we have stated are largely overcome and the efficiencies which we have stated are achieved. Using, as an illustration, the standard rifle chambrage, or cartridge case, which is known as the .300 H & H magnum we have found that by proper shoulder configuration a charge of about 20% above standard can be burned behind the standard 180 grain bullet, without substantial increase in maximum pressures, and with an increase in bullet velocity from about 3000 feet per sec. to approximately 3400 feet per sec., and an increase in bullet energy of about 27 per cent. The following description, taken in connection with the accompanying drawings, explains in detail a preferred and illustrative chamber configuration as applied, for instance, to the standard .300 H & H magnum rifle.

25 In the accompanying drawings:

Fig. 1 is a view showing in elevation cartridge ammunition in accordance with our invention;

Fig. 2 is an enlarged sectional view of the neck portion of such a cartridge, and

30 Fig. 3 is a similar sectional view of a modified form of the invention.

In Fig. 1 the body of the cartridge case is shown at 10 in rifle chamber 11. The shoulder which leads from the body to the neck 12 is designated 35 generally by the numeral 13. Neck 12, and bullet 130 are of standard size, the latter being illustrated as the standard diameter .30 caliber bullet. The rifle barrel 14 may either be the standard barrel 10 may be free-bored, as shown at 15, for a distance of about 2" from its breech end, with the rifling lands 16 beginning at that forward point.

The case body as here shown has a cylindric external diameter about the same as the maximum diameter of the standard case referred to; and about the same length. The body, instead of being heavily tapered in its forward part, is preferably almost cylindric up to the shoulder 13, having only a very slight taper (not shown). The substantially full cylindric form up to the shoulder gives the additional charge capacity, and leaves it substantially wholly for the shoulder to form the reduction between the full sized body and the neck. The particular proportionate length and diameter of body here shown are not

controlling in my invention; the proportions may be chosen in any case to engender the highest efficiency; and those shown are merely typical. Figs. 2 and 3 are drawn quite accurately to scale at twice actual size of this typical design of ammunition for a .300 H & H magnum rifle, which of course is necessarily rechambered. The actual dimensions, which we have used, are as follows:

	Inch, externally
Body diameter at shoulder	.500
External neck diameter	.340
Bullet diameter	.308
The wall thickness of the cartridge case, shown somewhat exaggeratedly in the drawings, is approximately	.016
The internal body diameter is consequently	.468
And the internal neck diameter	.308
The difference between body and neck diameters (either external or internal) is	.160

The distance by which the base of bullet 130 is seated in neck 12 is immaterial to our invention; but the spatial relation of the base plane 130a of the bullet to the shoulder configuration is of some importance.

The shoulder configuration as shown, is generated as follows: Taking a point S on the exterior of the case as an initial point, a line is drawn at an angle of 45° to the axis of the case, from that point S to the point N where the line intersects the exterior of neck 12. The perpendicular bi-sector A—B of line S—N is then erected and the center point O then chosen to make the distance O—S or O—N equal to approximately .160". With O as a center the arc 20 is struck between S and N, and this arc represents the external section line of the shoulder 13. Another arc 21, struck on the same center, and at a radius increase equal to the case wall thickness, then represents the inner line of the section of the shoulder. The radius of that inner section line is either approximately .160 or may be slightly more, as it is in the actual ammunition which we have made and tested. In Fig. 2 the arc 21 is shown extended in dotted lines at 21a, and that arc extension 21a intersects the inner surface of neck 12 at approximately the bullet base plane 130a. The resulting distance from point N to the plane of 13a is approximately .154 inch.

One characteristic feature of our shoulder formation is that a relatively abrupt shoulder is formed in the chambrage at the point 22 where the internally convex curve 21 meets the inner chamber wall of the body. The internal included angle at 22 (that is, the angle, internal of the case, measured between the inner surfaces of the body and the shoulder formation) is less than 135°. Another feature is the continuous internal convexity of the shoulder surface 21 substantially throughout its section in an axial plane such as the plane of the paper in Fig. 2 (preferably a circular arc on a radius of the proportionate dimension stated). And a third feature of the shoulder configuration is that it is not tangent to the neck at the point N, but is, in full effect, the end portion of the contracting intake of a venturi formation which, if extended, would have its maximum constriction in a plane which is represented by the dotted line at 23 rearwardly of bullet face 130a, and would then open out to the full diameter of the bullet at the plane of 130a. In the form of Fig. 2, the inner surface of the shoulder formation, being non-tangent to the inner surface of the neck, makes an angle

with the neck surface of more than 180° as measured internally of the cartridge wall.

In fact the functional performance of our chambrage seems to be very much, if not wholly, as if the Venturi formation of shoulder 13 were continued on to the plane of the bullet base as illustrated in Fig. 3. In that figure the shoulder 13a is generated in the same manner as in Fig. 2, with the curved shoulder carried on forward to the plane of 130a, and with a resulting maximum Venturi constriction in the plane indicated at 23. The action is very much, if not wholly, as if the chambrage were constructed and proportioned as in Fig. 3. In fact we have ascertained that if a cartridge case constructed like Fig. 2 is repeatedly re-loaded and shot, the neck portion between the transverse plane of point N and the plane of 130a becomes quite definitely thickened between the wall of the rifle chamber and the inside of the neck so that the inside is similar to the interior configuration shown in Fig. 3, except that the neck necessarily shortens to provide for the increased wall thickness. Thus the shoulder formation of Fig. 3 is included within our invention in its broader aspects. The form of Fig. 2 however seems to have all of the functional advantages of Fig. 3, and in addition is easier to manufacture.

In ordnance which uses no ammunition case, our chambrage which is here described as the interior of the case will be applied directly to the gun. In that instance the interior of case neck 12 becomes physically what it here is in effect—the rearward or breech end of the gun bore. Or, amounting to the same thing, when the cartridge is in the gun chamber, the cartridge case may be considered as a liner and, thus, as forming the walls of the gun chamber including the described shoulder and the wall of the rearward portion of the bore containing the projectile.

We cannot say that the following explanation is the ultimately true and full account of the functions of our chambrage which lead to its demonstrated improvement in efficiency; but we have come to the following conclusions as a result of extended comparative tests which we have carried on between standard ammunition and our improved ammunition. Standard factory .300 H & H magnum ammunition carries a charge of 62½ grains of IMR nitrocellulose powder, while our cartridge is regularly loaded with 75 grains of the same propellant. It has been demonstrated by repeated tests that with our ammunition there is far less tendency for the burning powder to follow forward after the projectile; and that prevention we believe to be due largely, if not wholly, to the particular angular Venturi formation which promotes the flow of gases forward and inhibits the flow of solids in a forward direction but drives them back alongside the case wall towards the rear as the gases issue out the center through the effective constriction of the Venturi formation. The unburnt charge is thus held back while the generated pressure causes gas to flow forwardly, controlled by the Venturi formation; the gaseous stream apparently contracting at the virtual Venturi neck in the plane 23 and then expanding to the full diameter of the bullet at the bullet base.

Due to the flow control of the Venturi shoulder formation, the chamber pressures seem to initially build up more slowly, with the combustion controlled, while the projectile is first put into motion and gathering speed. To allow the projectile to gather initial speed freely we prefer, although

it is not at all necessary, to free-bore the rifle bore for a short distance as we have stated.

The Venturi formation allows the expanding pressure gases to enter the neck and bore with the minimum turbulence and restraint; the gases flow freely in a smooth stream forwardly behind the projectile. Due to that free flow, devoid of turbulence, there is a relative absence of surging which minimizes the rearward propagation of pressure waves. That wave propagation, in ordinary chambrages, is one of the factors which causes detonation of the charge and inhibits controlled slow combustion. The relative elimination of wave pressures enables us to burn the larger charge slowly without increasing peak pressures; and results also in longer maintenance of the maximum pressures after they are reached.

The final resulting facts, ascertained from comparative tests, may be briefly summed up as follows.

The substantially increased weight of charge is burned without any substantial increase in peak pressures, and fired in the same firearm gives no substantially measurable increase in peak recoil as compared with the standard ammunition.

The barrel of the firearm using our chambrage heats up in the forward half of the barrel first and most; indicating maximum bore friction at that point, which comes from maximum pressure reached there; while all standard and other chambrages cause maximum heating in the rear quarter of barrel length.

Muzzle velocity of the standard 180 grain bullet is increased from approximately 3000 ft. per sec. to 3400 ft. per sec.; with a resultant increase in energy from 3600 ft. lbs. to 4625 ft. lbs.

The energy increase is approximately 27% plus. The efficiency increase in energy per unit weight of powder, measured by the energy increase over the powder increase, is approximately 7% plus. Similar comparative tests with standard .30-06 U. S. service ammunition have shown energy increases of better than 30%, with efficiency increases up to 11%.

It will be understood that the dimensional and other specific figures which we give are merely illustrative of the invention as applied to a specific firearm. The invention is applicable to ordnance of all calibres and kinds.

Our invention will also be understood as relating to chambrage, whether or not the chamber is formed directly in the gun or is formed as the interior of a case inserted in the gun. The following claims are intended to cover the chambrage in either of its physical forms.

We claim:

1. In a gun barrel having a projectile receiving

bore and a coaxial combustible-charge-receiving walled chamber of larger diameter than the bore, a coaxial annular shoulder surface joining the walls of the chamber and bore, said surface being internally convex in an axial plane and having substantially circular curvature, said surface being non-tangent to both the chamber and bore walls and the chordal line of the shoulder arc running through its intersections with the chamber and bore walls extending inwardly and forwardly of the barrel axis.

5 2. A gun barrel as specified in claim 1, in which the radius of curvature of said shoulder surface corresponds substantially to the difference between the diameters of said chamber and bore.

10 3. A gun barrel as specified in claim 1, in which said chordal line extends at about 45° to the barrel axis.

4. In cased ammunition having a case forming

20 a forward projectile receiving neck and a coaxial propellant containing body chamber of larger diameter than the neck, a coaxial annular shoulder surface joining the walls of the chamber and neck, said surface being internally convex in an axial plane and having substantially circular curvature, said surface being non-tangent to both the chamber and neck walls and the chordal line of the shoulder arc running through its intersections with the chamber and bore walls extending inwardly and forwardly of the case axis.

25 5. A case as specified in claim 4, in which the radius of curvature of said shoulder surface corresponds substantially to the difference between the diameters of said chamber and neck.

30 6. A case as specified in claim 4, in which said chordal line extends at about 45° to the case axis.

RALPH WALDO MILLER.
EDWARD BADEN POWELL.
